(57) **CLAIM**

I claim the ornamental design for a dispenser, as shown and described.

DESCRIPTION

FIG. 1 is a top perspective view showing a dispenser in accordance with our new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevation view thereof;

FIG. 8 is a right side elevational view thereof;

FIG. 9 is a reduced scale top perspective exploded view thereof;

FIG. 10 is a reduced scale bottom perspective exploded view thereof;

FIG. 11 is a front elevational exploded view thereof;

FIG. 12 is a rear elevational exploded view thereof;

FIG. 13 is a top plan exploded view thereof;

FIG. 14 is a bottom plan exploded view thereof;

FIG. 15 is a left side elevational exploded view thereof; and,

FIG. 16 is a right side elevational exploded view thereof.
